SIGNALING SYSTEM

John H. Voss, Berwyn, Ill., assignor, by mesne assignments, to Associated Electric Laboratories, Inc., Chicago, Ill., a corporation of Delaware

Application October 13, 1930, Serial No. 488,363

9 Claims. (Cl. 177—353)

This invention relates to electric signaling systems in general, but more particularly it relates to those signaling systems in which the transmitted signals comprise series of electrical impulses corresponding to numbers or letters, which impulses are employed to operate selecting or translating mechanisms which cause certain ones of a plurality of lamps in a lamp panel to glow and thereby exhibit the corresponding numbers or letters through a glass panel.

The requirements for signaling systems in the present era are both many and varied and to meet those requirements, many signaling systems have been devised. Chief among the requirements is a requirement for a signaling system which will automatically display a plurality of signals one at a time and for a predetermined period of time upon a single display panel, but which signals may be recalled if desired and be caused to be re-displayed. The provision of an electric signaling system to meet this chief requirement has been assumed as the principal object of the invention.

Among the many features of this invention is the arrangement whereby the automatic display of the plurality of signals may be arrested in order that a selected one of the plurality of signals may be recalled and displayed continuously for any desired length of time.

This feature and others which are not being individually pointed out at this time will be apparent from the detailed description which is to follow when it is studied in conjunction with the accompanying drawings comprising Figs. 1 to 3, inclusive, which by means of the usual circuit symbols diagrammatically depict the signaling system of this invention.

It is contemplated to use the system of this invention in a factory or business house which has a private automatic telephone exchange system and in which it is required that certain information be transmitted to a central point from various departments in the organization, which information may be used for the coordination of the efforts of those various departments. In the system shown in the drawings, the amount of equipment required to complete the system has been reduced by utilizing the private automatic telephone equipment to a large extent.

For convenience in describing the operation of the system of this invention, it will be assumed that, in the place where the system is to be used, there are ten departments which are to transmit to a supervisor, three digit numbers constituting signals which will supply the supervisor with the

desired information. Accordingly, a register, upon which signals may be stored while waiting to be displayed upon a display panel before the supervisor, has been allotted for the individual use of each of the ten departments.

In the drawings, Fig. 1 shows the register selecting mechanism comprising a group of relays and the register selecting switch RS. This equipment is selectable to all of the departments in a manner about to be described in connection with one of the departments represented by station A. The equipment is selectable to station A by means of the automatic line-switch C and the Strowger switch D, which switches, because of their being so well known in the telephone art and because they do not constitute a part of this invention, have not been shown in detail but have merely been represented by the rectangles. The station A, besides being provided with the usual telephone talking and listening instrumentalities, is provided with a calling device or impulse sender S with which stations are provided in automatic telephone systems. This calling device or impulse sender S has been represented by a pair of normally engaged impulse springs, which in the well known manner are separated by an impulse cam one or several times in quick succession to transmit one or a series of impulses. This calling device is utilized first to operate the switch D to select the relay group, second to operate the switch RS to select a certain register, and third to transmit signals to the selected register.

Fig. 2 shows one of the ten registers accessible to the register selector RS. This register comprises the sequence selecting switch SS and the three digit selectors which are the hundreds selector HS, the tens selector TS, and the units selector US. Hereinafter, this register, since it is shown as connected to the first set of bank contacts of the register selector RS, will be termed register group No. 1, and it will be assumed that this register is allotted to the department represented by station A.

The first of the three series of impulses received by the register group No. 1 during signal transmissions will be routed by the sequence selector SS to the hundreds selector HS, while the second and third series will be routed by the sequence selector SS to the tens selector TS and the units selector US, respectively.

The signal display panel represented by the rectangle in the upper right-hand corner of Fig. 2 is the panel upon which the signals are displayed and which is located in view of the su-

pervisor. This panel comprises the three rows of ten lamps each, which are entitled the hundreds, tens and units rows. These lamps when lighted will exhibit the numerals by which they are indicated in the drawings, through the glass panel in the well known manner. The ten lamps in the hundreds row are connected to the ten contacts of the hundreds selector HS in proper order so that when the hundreds selector is set upon its first contact it will be in connection with signal lamp No. 1 and when on its tenth contact will be in connection with signal lamp No. 0. The ten conductors connecting the ten lamps in the hundreds row with the hundreds selector have been represented by the single conductor 74 in order to avoid complication of the drawings. In a like manner the ten lamps in the tens row are connected to the bank contacts of the tens selector TS as represented by the conductor 75, while the ten lamps in the units row are connected to the bank contacts of the units selector US as presented by the conductor 76.

Inasmuch as the ten register groups are identical with each other, it is thought that the showing of register group No. 1 will suffice for a complete understanding of the system.

As indicated by the arrows on conductors 74, 75 and 76, the ten lamps in the hundreds row of the signal display panel are multiplied to the bank contacts of all of the hundreds selector switches HS, while the ten lamps in the tens row and the ten lamps in the units row are, respectively, multiplied to all of the bank contacts of the tens selector switches and to the bank contacts of all the units selector switches.

How only one signal will be displayed upon the signal display panel at a time with the lamps multiply connected to all of the registers will be evident as the description progresses.

Towards the lower right-hand corner of Fig. 2 is represented a second lamp panel which is termed the supervisor's display panel. This panel comprises two rows of lamps, the upper row of which is termed the green set-up lamps while the lower row is termed the red display lamps. There will be as many pairs of lamps in this panel, each pair comprising one of the green set-up lamps and one of the red display lamps, as there are register groups. This panel is located at the supervisor's station and is for the purpose which will be later evident.

Fig. 3 shows what is termed the "common equipment" which controls the selection of the signal to be displayed and the length of time which that signal will be displayed. This common equipment comprises the display selector DS which determines the register signals to be displayed, and the display timing switch DTS which times a display. The relays intermediate these two switches control the operation thereof.

Towards the upper right-hand corner of Fig. 3 is a group of non-locking type keys which correspond in number to the number of register groups, there being one such key for each register group. By the operation of one of these keys, the automatic operation of the common equipment will be arrested and the signal registered on the corresponding register group will be displayed continuously as long as the register key remains in its operated position. This operation will be explained in detail later.

When the operator at the station A, Fig. 1, desires to register a signal upon the register allotted to his department, which it has been assumed is register group No. 1, Fig. 2, and have that

signal automatically displayed upon the signal display panel, he will remove the receiver R from the switch-hook and thereby close the loop circuit over conductors 1 and 2 for the automatic lineswitch C which is individual to the line connecting the station A with the private automatic exchange. Lineswitch C thereupon functions in the well known manner to select a trunk leading to an idle switch, such as the Strowger switch D, to prepare that switch for operation under control of the calling device S. The switch D is assumed to be a selector switch which is well known in the telephone art. No particular type of selector switch other than one which permits loop impulsing has been selected for use herein since there are a great many such switches which may be used.

After the operator has operated the calling device S in accordance with the one digit required to elevate the wipers of the switch D to the proper level of bank contacts and the selector has automatically rotated its wipers into engagement with the contacts of the line conductors 3 and 4 and the private normal conductor 5 leading to the relay group associated with the register selector RS, a loop circuit is completed through the selector D for the relay 6 by way of line conductors 3 and 4. Relay 6 immediately operates and attracts its armatures 7 and 8 into engagement with their make contacts thereby, at its armature 7, completing the circuit for the slow-to-release relay 9, and, at its armature 8, preparing a circuit for the slow-to-release relay 18 for a purpose which will be described subsequently.

Relay 9 immediately operates and at its armature 10 connects ground to the private normal conductor 5 to hold the switch D and to mark the relay group busy to any other switch similar to the switch D. At its armature 11 relay 9 prepares an impulsing circuit through the series relay 12.

Since it is the register group No. 1 upon which the operator wishes to register the signal 345, for example, he will next operate his calling device to send one impulse through the selector D to relay 6. Relay 6 follows this impulse by deenergizing and retracting its armatures 7 and 8, the retraction of armature 8 being without any effect at this time. However, at armature 7 a ground impulse is transmitted by way of armature 11 and make contact of relay 9, winding of relay 12, armature 21 and resting contact of relay 20, winding of operating magnet 25 of the register selector RS, to battery. The operating magnet 25 thereupon energizes and advances the wipers 27 and 28 into engagement with the first set of contacts.

Register selector RS is of the well known rotary type of switch whose wipers have a normal position and are moved in a step-by-step manner from that normal position upon the energization of the operating magnet 25, and whose wipers are returned to the normal position in the opposite direction upon the energization of the release magnet 26. Switches HS, TS and US are the same type of switches.

Relay 6 reenergizes upon the termination of the impulse and by attracting its armature 7, opens the circuit of the series relay 12 and the operating magnet 25 which magnet 25 thereupon de-energizes.

Series relay 12 energized in series with the operating magnet 25 when the impulse is transmitted to the operating magnet by relay 6 and attracts its armatures 13 and 14 to complete the circuit

for the slow-to-release relay 18 at its armature 13 and to open a point in the circuit of relay 20 at its armature 14. Because relay 12 is slow-to-release it will remain operated an interval after relay 6 has reenergized and opened the impulsive circuit, likewise, relay 12 also because of the slow-to-release feature will remain operated during the transmission of a series of impulses should the relay 6 be alternately deenergized and energized 5 a plurality of times in quick succession to transmit a plurality of impulses. Relay 18 energizes when its circuit is completed by relay 12 and attracts its armature to open a point in the circuit of the slow-to-release relay 15 and the tone 10 relay 19.

When relay 12 finally releases, at its armature 14 it completes the circuit of the relay 20 through the off-normal springs 28' of the register selector RS, which springs are allowed to move into engagement with each other when the wipers 27 and 28 of the register selector are stepped from their normal position. The circuit of relay 18 is opened when armature 13 of relay 12 is retracted but this relay remains operated for an interval, 20 because of the slow-to-release feature, for a purpose which will be evident as the description progresses.

Relay 20 operates when its circuit is completed by way of armature 14 and resting contact of relay 12, and off-normal springs 28', and at its armature 21 transfers the impulsive circuit from the operating magnet 25 to the wiper 27 of register selector RS and consequently to conductor 29 which leads to the register group No. 1. Relay 35 20 at its armature 22 completes a locking circuit for itself which is independent of the armature 14 and resting contact of relay 12, while at its armature 23 it connects the winding of relay 18 to the wiper 28 and consequently to the conductor 40 30 leading to the register group No. 1 by way of armature 17 and resting contact of relay 15, armature 13 and resting contact of relay 12, and armature 8 and make contact of relay 6.

Relay 18 restores its armature into engagement 45 with its resting contact an interval after its circuit was opened at armature 13 of relay 12 and thereby completes the circuits of relays 15 and 19 from ground by way of make contact and inner-upper armature of relay 20. These relays immediately operate.

Relay 15 in operating, at its armature 16 prepares a circuit for release magnet 26 of the register selector RS and, at its armature 17, opens a point in the circuit of relay 18 to prevent operation 55 of this relay the next time relay 12 operates.

Relay 19 is a differential relay, that is, its upper and lower windings are equal but have opposite effects upon the relay. Relay 19 operates when 60 the circuit of its lower winding is completed by relay 18 and at its armature completes the circuit of its upper winding. This energizes the upper winding, neutralizing the effect of its lower winding. Relay 19 thereupon restores its armature and opens the circuit of its upper winding. Since 65 the lower winding of relay 19 is still energized, it will again attract its armature and complete the circuit of its upper winding again. This again neutralizes the effect of the lower winding and the armature is again retracted. This action of relay 19 will continue as long as the circuit of the lower winding remains completed, and in so doing, the relay acts as a buzzer, sending a tone over the conductor 3 to the station A. The operator at 70 that station, upon hearing this tone, is informed

that everything is in readiness to receive the signal which he is about to transmit.

The operator will now operate his calling device S to transmit three impulses in accordance with the first digit "three" of the signal 345, and thereafter will operate his calling device to transmit a series of four impulses and another series of five impulses. This operation causes the relay

6 to transmit three impulses through the series relay 12 and over the wiper 27 of switch RS and conductor 29 to the register group No. 1. Since

the sequence selector SS of the register group No. 1, Fig. 2, has its wipers 42 and 43 in engagement with its first set of contacts, the three impulses over the conductor 29 will be routed

by way of wiper 42 of sequence selector SS, over conductor 45 to the operating magnet 48 of the hundreds selector HS. The operating magnet 48 will energize and deenergize three times in quick

succession to move the wiper 54 of the hundreds selector HS into engagement with its third contact, which movement of wiper 54 allows the off-normal springs 55 to move into engagement with each other. Relay 34 also receives the impulses

and upon the reception of the first one energizes 100 and attracts its armatures 35 and 36. By the attraction of its armature 35 it completes a circuit for its upper winding which, in the well known manner, makes the relay 34 a slow-to-release relay, while at its armature 36 it completes the circuit for relay 37. Relay 37 is similar to the relay 34 and at its armature 38 it completes a circuit for its upper winding which makes

that relay slow-to-release and at armature 39 it prepares a circuit for the operating magnet 40 110 of the sequence selector SS. Since relay 34 is made slow-to-release by the completion of the circuit of its upper winding, this relay will remain in its energized position throughout the

series of impulses transmitted over the conductor 29 to the register group. When the first series of impulses is completed, relay 34 will finally restore 115 and at its armature 36 open the circuit of slow-to-release relay 37 and complete a circuit for the operating magnet 40 of the sequence selector SS

by way of armature 39 and make contact of relay 37, since the relay 37 is also slow-to-release and maintains its armature 39 in engagement with its make contact for a short interval after its circuit is opened by the retraction of armature 36

120 of relay 34. Therefore, operating magnet 40 receives one impulse which causes it to move the wipers 42 and 43 of the sequence selector SS into engagement with the second set of bank contacts, thereby connecting the impulse conductor 29 to conductor 46 which leads to the operating mag-

net 50 of the tens selector TS and allows the off-normal springs 44 to engage each other to connect ground in multiple with the off-normal springs 55 of the hundreds selector HS to conductor 33 for a purpose which will be described

later.

When the next series of four impulses, corresponding to the second digit of the signal, is transmitted by the relay 6 over the impulse conductor 29, the relays 34 and 37 will again operate and remain operated until the impulse series is completed, and the magnet 50 of the tens selector TS will receive four impulses by way of

130 conductor 46 and wiper 42 of sequence selector SS to move the wiper 56 of the tens selector TS into engagement with the fourth contact of its bank, which movement allows the off-normal springs 57 to engage each other. At the end of

135 this series of impulses the relays 34 and 37 again function to transmit an impulse to the operating

140

145

150

magnet 40 of the sequence selector SS to move the wipers 42 and 43 into engagement with the third set of bank contacts, thereby connecting the impulse conductor 29 to conductor 47 leading to the operating magnet 52 of the units selector US.

When the third series of five impulses is received over the conductor 29, the relays 34 and 37 again operate and this time the operating magnet 52 of the units selector US operates in response to the impulses and moves the wiper 58 into engagement with the fifth contact of its bank, this movement allowing the off-normal springs 59 and 62 to engage each other. At the completion of the impulse series, relays 34 and 37 again function to transmit an impulse to the operating magnet 40 of the sequence selector SS to move the wipers 42 and 43 into engagement with the fourth set of contacts of the banks. In this position of wiper 42, a portion of the impulse transmitted to operating magnet 40 is transmitted by way of wiper 43 to conductor 73, which is connected to the fourth bank contact, and consequently to the upper winding of relay 62. Relay 62 immediately operates and at its armature 63 completes a locking circuit for itself by way of conductor 61 and resting contact and armature 32 of relay 31, so that relay 62 will remain operated after relay 37 opens the circuit of the operating magnet 40 at its armature 39. Relay 62 also attracts its armatures 64 to 66, inclusive.

When the units selector US was operated and the off-normal springs 60 were closed, the obvious circuit for the No. 1 green set-up lamp was completed to indicate to the supervisor that a signal has been transmitted from station A and registered upon the No. 1 register group.

By the positioning of the wipers 54, 56, and 58 of the digit selecting switches HS, TS, and US, respectively, circuits are prepared for the No. 3 lamp in the hundreds row, the No. 4 lamp in the tens row, and the No. 5 lamp in the units row in the signal display panel. Inasmuch as the relay 72 has not yet been operated these lamps will not light.

Since the operator at station A has completed the transmission of the signal, he will replace the receiver R upon the switch-hook and thereby open the loop circuit to cause the release of the lineswitch C and the selector D, and also the release of the relay group. When the receiver R is replaced, the loop circuit over conductors 3 and 4 for relay 6 is opened and this relay restores to normal, opening the circuit of the slow-to-release relay 9 at its armature 7. Relay 9 restores and at its armature 10 removes ground from private normal conductor 5, allowing the selector D and lineswitch C to restore and condition station A for regular telephone service. Since relay 15 is operated, the release of relay 9 completes, at its armature 10, the circuit for the release magnet 26 of the register selector RS by way of armature 16 and make contact of relay 15. Release magnet 26 thereupon operates to restore the wipers 27 and 28 to their normal positions and to disengage the off-normal springs 28', thereby opening the locking circuit of relay 20. Relay 20, thereupon restores and at its inner-upper armature opens the circuits of the relay 15 and the tone relay 19. Relay 15 in retracting its armature 16 opens the circuit of the release magnet 26 and the equipment is now in readiness to again be taken into use by a selector switch such as the switch D.

Besides completing a locking circuit for itself

at its armature 63 when it energizes, relay 62 at its armature 65 connects the conductor 68 with conductor 70 and at its armature 66 connects ground to the start conductor 71. The attraction of armature 64 of relay 62 into engagement with its make contact is without particular effect at this time. The attraction of armature 66 removes ground from the conductor 69 for a purpose which will be described later.

Should another department, that, for example, to which the register group No. 2 is allotted, have information at this time to transmit to the supervisor, the person in that department whose duty it is to transmit such information will remove the telephone receiver R at his station from the hook to cause the lineswitch C individual to that station to select a switch such as the selector D and by the operation of his calling device will cause the switch D to connect that station with the equipment of Fig. 1, whereupon the relay 6 will energize and prepare the impulsing circuit for the motor magnet 25 of the register selector RS. Since it has been assumed that the register group #2 is the desired register group, the operator at the station will operate his impulse sender S to transmit two impulses to the relay 6, which relay will then transmit two impulses to the motor magnet 25. As a result, the wipers 27 and 28 of the register selector RS will be positioned on the second bank contacts to which are fastened the conductors 29' and 30' leading to the No. 2 register group.

The No. 2 register group and the other register groups have not been shown in the drawings because it is believed that a showing of them would unnecessarily complicate the drawings since the register groups are identical with the No. 1 register group and respond to impulses exactly as just described in connection with register group No. 1.

Therefore, after the digit selectors of register group No. 2 have been set in accordance with the transmitted signal, the relay 62 of that register group is operated to lock itself in operated position, to disconnect ground from the conductor 67', to connect the conductor 68' to the conductor 70 of that register group, and to connect ground to the conductor 71 of the No. 2 register group.

When the wiper of the units selector of the No. 2 register group is moved from its normal position, the off-normal springs associated therewith are allowed to engage each other and thereby complete the circuit for the No. 2 green set-up lamp to indicate to the supervisor that a signal is registered in the No. 2 register group.

Returning now to the operation of the equipment after the relay 62 of No. 1 register group operated, when ground is connected to the start conductor 71, the circuit of the start relay 86 of the common equipment of Fig. 3 is completed by way of wiper 100 of the display timing switch DTS, conductor 105, armature 92 and resting contact of relay 91, through the winding of relay 86 and through a non-inductive resistance to battery. Relay 86 operates at armature 87 and completes a locking circuit for itself by way of conductor 104 to the start conductor 71 independent of the wiper 100 of the display timing switch DTS, and at its armature 88 completes a circuit for the slow-to-release relay 81 in series with the marginal motor magnet 77 of the display selector DS. Relay 81 thereupon operates, but, because of the relatively high resistance of this relay, the marginal motor magnet 77 does not operatively energize. Upon ener-

gizing, relay 81 at its armature 83 connects ground to conductor 68 by way of wiper 79 to complete the circuit of relay 72, Fig. 2, by way of armature 65 and make contact of relay 62 and conductor 70, at its armature 84 completes the obvious circuit for the slow-to-energize relay 93, at its armature 85 connects the wiper 80 of the display selector DS with the wiper 101 of the display timing switch DTS by way of conductor 107, and at its armature 82 prepares a circuit for short-circuiting the start relay 86.

Relay 72 energizes when its circuit is so completed and connects ground to the wipers 54, 56 and 58 of the digit selectors and connects ground to the No. 1 red display lamp in the operator's display panel, thereby causing the signal 345 corresponding to the setting of the digit selectors to be exhibited upon the display panel and the No. 1 red display lamp in the operator's display panel to glow to indicate to the supervisor that the signal stored in the No. 1 register group is being exhibited in the display panel.

When the start relay 86 energized, at its armature 90 it completed the obvious circuit for the audible signal AS to attract the supervisor's attention to the fact that a signal is being exhibited.

When the circuit of the slow-to-energize relay 93 is completed by the relay 81, this relay operates and completes the circuit for the slow-to-energize relay 94 in multiple therewith. Relay 94 energizes after an interval and completes the obvious circuit for the slow-to-energize relay 95. When relay 95 operatively energizes at its armature 96 it short-circuits the winding of relay 93 to cause that relay to deenergize, which it thereupon does and opens the circuit of relay 94. Relay 94 also deenergizes and opens the circuit of relay 95, which, when it deenergizes, at its armature 96 removes the short-circuit from relay 93. Relay 93 again energizes when the short circuit is removed and again causes the energization of the relay 94 to complete the same cycle of operations.

When the relay 95 is energized, at its armature 97 it completes a circuit for the motor magnet 98 of the display timing switch DTS from ground by way of armature 90 and make contact of relay 86, make contact and armature 97 of relay 95, wiper 102 of display timing switch DTS, and winding of motor magnet 98 to battery. The motor magnet 98 energizes in this circuit and prepares to step the wipers 100 to 102, inclusive, of the display timing switch DTS onto its next set of bank contacts upon its deenergization.

The display timing switch DTS and the display selector DS are of the well known type of rotary switches whose wipers move in a forward direction only and are moved in a step-by-step fashion upon the deenergization of the motor magnet.

Thus, when the relay 95 deenergizes upon the opening of the circuit with the deenergization of relay 94 in the cycle of operations just explained, the circuit of the motor magnet 98 is opened with the retraction of armature 97 and the wipers of the display timing switch are advanced into engagement with the second set of contacts of their bank. When the wipers of the display timing switch DTS move from their normal or starting position, the off-normal springs 103 close to prepare a homing circuit for the timing switch.

Inasmuch as the relays 93, 94 and 95 will continue in their cycle of operations as long as relay 81 remains operated, the motor magnet 98

of the display timing switch DTS receives an impulse upon each energization of the relay 95 and consequently the wipers of the timing switch will be stepped from contacts to contacts. Because of the slow-to-energize feature of relays 93, 94, and 95, a considerable time interval is inserted between impulses transmitted to motor magnet 98. After the wipers 100 to 102, inclusive, have taken their fourth step, the motor magnet 98 can no longer be influenced by the operation of the relay 95 since the wiper 102 when on its fifth bank contact does not connect with the conductor leading to the winding of the motor magnet 98. Consequently the display timing switch DTS will remain in this position until some other circuit for the motor magnet 98 is completed.

With the wiper 101 in its fourth position, that is in engagement with its fifth bank contact, ground connected to that bank contact is connected by way of wiper 101, conductor 107, make contact and armature 85 of relay 81, wiper 80 of display selector DS, to conductor 67 and armature 64 and make contact of relay 62 to short-circuit the lower or locking winding of that relay. Consequently, relay 62 restores and retracts its armatures 63 to 66, inclusive. The retraction of armature 65 opens the circuit of the relay 72 which relay thereupon deenergizes and extinguishes the lighted lamps in the signal display panel and the No. 1 red display lamp in the supervisor's display panel. At its armature 66, the relay 62 replaces ground on conductor 69, which ground, since armature 82 of relay 81 is in engagement with its make contact, short-circuits the start relay 86 of the common equipment. Relay 86 thereupon deenergizes and at its armature 87 opens its locking circuit and at its armature 88 opens the circuit of the slow-to-release relay 81. At its armature 90, relay 86 completes the homing circuit for the display timing switch DTS by way of off-normal springs 103 and self interrupting contacts 99 of motor magnet 98. In the well known manner, motor magnet 98 functions to step the wipers 100 to 102, inclusive, to their starting positions, that in 120 which they are shown in the drawings, in a buzzer-like fashion. When the wipers reach their starting position, the off-normal springs 103 are opened and the homing circuit of the display timing switch is also opened. Therefore, the 125 display timing switch will remain in this starting position until relays 93 to 95, inclusive, again function to transmit impulses to the motor magnet 98.

Relay 81 deenergizes a short interval after 130 its circuit is opened at armature 88 of start relay 86 and at its armature 82 removes the short-circuit from the start relay 86 and at its armature 84 opens the circuit of the relay 93 and whichever of the relays 94 and 95 are operated at that time, to prevent further transmission of impulses to the motor magnet 98.

If at this time there is a signal registered upon one of the other registers, register No. 2 for example, and waiting to be displayed upon the signal display panel, the relay 62 associated with that register will be in its operated position and the register start conductor 71 will have ground thereon. Therefore, when the wiper 100 of the display timing switch DTS reaches its home position and the relay 81 has retracted its armature 82 to remove the short-circuit from the relay 86, the circuit of relay 86 will again be completed over conductor 105 and wiper 100 and this relay will again operate. Since the relay 62 of the reg-

ister group No. 1 is in its retracted position, ground is connected by way of armature 64 and its resting contact to conductor 67. This ground operates the marginal motor magnet 77 of the display selector DS, when the relay 86 attracts its armature 89, to step the wipers 78 to 80, inclusive, into engagement with the second set of contacts of its bank. This circuit of motor magnet 77 includes the wiper 80, armature 85 and resting contact of relay 81, and make contact and armature 89 of relay 86. The armature 89 of relay 86 is so adjusted that it will engage its make contact before the armature 88 of relay 86 engages its make contact upon the energization of the relay 86. By this arrangement it is assured that relay 81 will be short-circuited and that the motor magnet 77 energizes it operates its self-interrupting contacts to cause its deenergization and the stepping of the wipers of the display selector DS. Since it is assumed that the signal waiting to be displayed is registered in register group No. 2, when in engagement with its second bank contact wiper 80 will not encounter ground upon the conductor 67' since the relay 62 associated with the second register group is in its energized position. Therefore, the relay 81 will no longer be short-circuited and it will energize in series with the marginal motor magnet 77, which magnet as stated before will not operate in series with the relay 81. Upon the operation of relay 81, the timing impulse relays 93 to 95, inclusive, are started into operation and the timing switch is again operated to time the display of register group No. 2 which is being displayed at this time because of the ground connected to conductor 68' by way of wiper 79 and make contact and armature 83 of relay 81, causing the energization of the relay 72 associated with the second register group. The No. 2 red display lamp is also lighted to indicate to the supervisor which signal is being displayed.

When the display timing switch has taken four steps, the relay 62 of the register group No. 2 will be short-circuited as explained in connection with register group No. 1, thereby causing the release of the start relay 86 of the common equipment which will cause the restoration of the timing switch to its starting position as previously explained. If at this time there are no more signals waiting to be displayed, the wiper 100 upon reaching its starting position will not encounter ground and the starting relay this time will remain inert. However, if there is still a signal waiting to be displayed on some register, other than registers No. 1 or No. 2, the equipment will again function and the display selector DS will be rotated step-by-step until it encounters the contact to which the conductor 67 of the register in which is stored the signal to be displayed, since, when the wiper 80 reaches this contact, no ground will be encountered and the relay 81 will no longer be short-circuited.

From the foregoing it can readily be seen that each time a signal is stored upon one of the register groups the common equipment will function to select that register group and cause the signal stored therein to be displayed for a period of time equal to that required for the timing switch TS to take four steps. Inasmuch as the relay 62 of each of these register groups is restored to its normal position after the signal registered therein has been displayed, that signal can be displayed only once since the wiper 80 of the display selector DS every time it comes in contact with a conductor 67 having ground thereon will

step its wipers onto the next contact. If there are ten register groups, and the register selector RS, Fig. 1, and the display selector DS, Fig. 3, have been shown as capable of handling only ten registers, only ten displays can be automatically displayed upon the display panel without changing one of the stored signals. However, this number of registers can be increased by providing larger capacity selectors for the register selector and for the display selector. Therefore, after the tenth display has been made, the wiper 100 of the display timing switch DTS upon reaching its starting position can no longer encounter ground since all of the relays 62 will be in their deenergized positions and no start conductor 71 will have ground connected thereto. Therefore, in order to have the common equipment again function a new signal must be registered in one of the register groups. However, if the supervisor desires at any time to recall one of the signals registered in one of the register groups, but which has already been displayed, he may have that signal displayed by the operation of the corresponding register key.

If it is the desire of the supervisor to have the signal registered in register group No. 1 displayed for the second time, he will operate the No. 1 register key in Fig. 3, completing the following circuit: ground, armature 88 and resting contact of relay 86, winding of relay 91, conductor 106, closed contacts of No. 1 register key, conductor 70, winding of relay 72, to battery. Relays 72 and 91 operate in this circuit and relay 72 connects ground to the wipers of the digit selectors to complete the circuits of the lamps in the display panel, while it also lights the red display lamp in the supervisor's display panel. Relay 91 at its armature 92 opens the initial energizing circuit of the start relay 86 to prevent any operation of this relay as long as the No. 1 register key is depressed should a new signal be registered upon one of the registers which previous to this time had not had a signal registered therein or in which a new signal was just registered.

Should the supervisor depress one of the register keys while a signal is being displayed upon the signal display panel, no action will take place until the signal being displayed has been displayed for the proper period of time because the start relay 86, being in its operated position during a display, at its armature 88 has removed the ground from the winding of relay 91. However, when the start relay 86 has been short-circuited at the completion of the proper time limit, as has been explained, the relay 91 will operate in series with the relay 72 of the register group corresponding to the register key depressed and at its armature 92 will open the circuit of the relay 86 to prevent operation of this relay when the display timing switch reaches its normal position should another signal be waiting to be displayed. As long as the No. 1 register key remains depressed, the relays 91 and 72 will remain operated and the signal will be displayed upon the panel. When the register key No. 1 is released, relays 91 and 72 will restore and the circuit of relay 86 will again be closed at the armature 92 of relay 91, while the signal lamps in the signal display panel and the red lamp in the supervisor's panel will be extinguished at the armatures of relays 72. If there is a signal waiting to be displayed at this time, the relay 86 will again operate from the ground encountered by wiper 100 and the display selector will function to select the proper register group.

Should the party at station A have a new signal to be displayed before the supervisor, he will again operate his calling device S in accordance with the proper digits to select the register selector and also to operate the register selector to select the No. 1 register group which is allotted to his station, in the manner previously described. This time, however, when the register selector has its wipers positioned in engagement with the contacts to which conductors 29 and 30 are connected, the wiper 30 will encounter ground because of the ground connected to conductor 33 through the off-normal springs of the sequence switch SS and the three digit selectors. Therefore, the relay 18 will have its circuit completed in the following circuit before it has had time to deenergize following the deenergization of the series relay 12 at the end of the impulse transmission of the impulse required to set the register selector RS. This circuit starts at the ground connected to the conductor 33 by the off-normal springs of the various selectors in Fig. 2 and includes the winding of relay 31, conductor 30, wiper 28 of selectors RS, armature 23 and make contact of relay 20, armature 8 and make contact of relay 6, resting contact and armature 13 of relay 12, resting contact and armature 17 of relay 15, and winding of relay 18 to battery. Relays 18 and 31 operate in this circuit and the relay 18 by maintaining its armature attracted prevents the operation of tone relay 19 as described, and the relay 31 at its armature 32 connects ground to the conductor 44 to complete the multiple circuit of the release magnets 41, 49, 51, and 53 of the selector switches of the register group No. 1. Since the operator at station A does not receive a tone he will delay the transmission of the impulses corresponding to the new signal until such tone is received. In the meantime, the release magnets 41, 49, 51, and 53 function to restore the wipers of the selectors to their home positions, in which positions the off-normal springs are operated and all ground connections are removed from the conductor 33. Thus the relays 31 and 18 no longer receive ground and they de-energize. Relay 18 now completes the circuit for the tone relay 19 and the relay 31 reconnects ground to conductor 61 to prepare the locking circuit for the relay 62.

The operator at station A now receives the tone generated by the relay 19 and he then proceeds to dial the three digits of the signal which it is desired to register upon register group No. 1. The register equipment in Fig. 2 responds to the impulses in exactly the same manner as previously described.

When the sequence switch SS takes its third step, ground will again be connected by way of wiper 43 and conductor 73 to the winding of relay 62 and this relay will again operate to connect ground to the conductor 71 to start the operation of the common equipment to select No. 1 register group and to display the new signal registered therein, upon the signal display panel.

At the end of the day, the supervisor may restore all registers to normal by momentarily depressing the register release key, Fig. 3, of each register, thereby connecting battery potential to the relay 31 of the associated register to cause that relay to operate and complete the release magnet circuits as previously described when that relay was operated in series with the relay 18, Fig. 1.

From the foregoing, it can be appreciated that a novel signaling system has been evolved

by means of which a plurality of signals may be registered and automatically displayed one at a time upon a single display panel and that each signal may be recalled for display at any time as long as that signal remains registered and that the automatic display of signals may be arrested when it is desired to recall a signal.

This invention having been thus described, what is considered new and what it is desired to have protected by Letters Patent is pointed out in the appended claims.

What is claimed is:

1. In a signaling system, a plurality of signal registers, some of which have signals registered therein, a single signal display panel, means for marking each register having a signal registered therein, means controlled by said registers for automatically finding each marked register, means associated with each register and operated for a predetermined interval of time responsive to the finding of its associated register for causing the signal registered therein to be displayed upon said panel and for a predetermined period of time, means for removing the marking of a register after the registered signal has been displayed to prevent said finding means again finding that register, and means for operating any one of said associated means to cause a registered signal to be displayed at will and for any desired length of time on said panel.

2. In a signaling system, a plurality of signal registers, some of which have signals registered therein, a single signal display panel, means for marking each register having a signal registered therein, means controlled by said registers for automatically finding each marked register, means associated with each register and operated for a predetermined interval of time responsive to the finding of its associated register for causing the signal registered therein to be displayed on said panel and for a predetermined length of time, means for then operating said first means to remove the marking of that register which has had its signal displayed to prevent the finding means again finding a register in which the registered signal had once been displayed, and means for arresting the operation of said finding means and for operating any one of said associated means to cause a desired registered signal to be displayed regardless of whether or not the signal had previously been displayed.

3. In a signaling system, a plurality of signal registers, impulse transmitting means, a register selector, impulse responsive means associated with said selector and responsive to the transmission of an initial series of impulses for operating said selector to select one of said registers, means responsive to such selection when the selected register has a signal registered therein for restoring the register to erase the signal and prepare the register for the registration of a new signal, means operating automatically responsive to the selection of a register having no signal registered therein for audibly signaling to indicate such selection, and means for preventing the operation of said audible signaling means when the selected register has a signal registered therein until that signal has been erased, said impulse responsive means thereafter responsive to succeeding series of impulses corresponding to a signal for operating the selected register to register that signal therein.

4. In a signaling system, a display board, a plurality of signal registers, a register finder,

means responsive to the registration of a signal in one of said registers for operating said finder to find said one register, means responsive to the finding of said one register for causing the signal registered therein to be displayed on said board for a given length of time only, and means for operating said last mentioned means at will to cause the signal registered in said one register to be displayed on said board.

10 5. In a signaling system, a display board, a plurality of signal registers, some of which have signals registered therein, means controlled by said registers for finding each register having a signal registered therein, means associated with each register and operated by said first means when the associated register is found to control said display board to display the signal registered in the found register, means controlled by said first means for terminating each display a given length of time after each register is found, and means operable at will to remove said first means from the control of said registers and to operate the second means associated with a desired register to thereby control said board to display the signal registered in said desired register.

6. In a signaling system, a signal display board comprising a plurality of signaling devices, a plurality of signal registers, each register comprising means set by impulses corresponding to a signal to prepare corresponding ones of said signaling devices for operation, a register finder controlled by said registers for finding each register having a signal registered therein, means associated with each register and responsive to the finding of its associated register by said finder for operating the signaling devices prepared for operation thereby to display on said board the signal registered in said associated register, means controlled by said finder for terminating each display a given length of time after each register is found, and means for operating at will the last mentioned means associated with any desired register to cause the signal registered therein to be displayed on said board.

45 7. In a signaling system, the combination with a plurality of signal registers having different signals registered therein and a common display panel for distinctively displaying different signals, of means operating automatically under the control of said registers for controlling said panel

to distinctively display each registered signal only once and for a definite length of time, and means operable at will to cause the distinctive display of any desired registered signal on the display panel, and a signal for each register operated as long as any signal is registered in its associated register.

8. In a signaling system, a display board, a plurality of signal registers, a register-finder switch, each register having a relay which is energized upon the registration of a signal therein to mark the register in the bank of said finder and to maintain itself energized, means effective upon the energization of one or more of said relays for operating said switch to find each register marked in its bank, a second relay associated with each register and responsive to the finding of the associated register by said switch for causing the signal registered in the associated register to be displayed on said board, timing means effective when said switch finds a marked register to deenergize the first-mentioned relay after a predetermined lapse of time to remove the marking of the register from said bank and to cause said second relay to remove the display from said board, and means for operating at will the second relay of any desired register having a signal registered therein regardless of whether or not that register is marked in the bank of said switch to cause the display on said board of any desired registered signal at will and for any desired length of time.

9. In a registering system, a plurality of signal registers, a register selector, an impulse transmitting device, means responsive to an initial series of impulses for operating said selector to select one of said registers, means responsive to such selection when the selected register has no signal registered therein for indicating such selection, said first means responsive to succeeding series of impulses corresponding to a signal to operate the selected register to register the signal therein, and a pair of relays cooperating responsive to the selection of a register having a signal registered therein, to restore the selected register, thereby erasing the signal therein and preparing the register for operation to register a new signal, and to delay the selection indication until the selected register has been restored.

JOHN H. VOSS. 126
